ATTORNEY

UNITED STATES PATENT OFFICE

IRA E. McCABE, OF CHICAGO, ILLINOIS

ADJUSTABLE MEANS FOR MOUNTING ELECTRICAL CONTROLS

Application filed December 22, 1930. Serial No. 503,978.

This invention relates to improvements in adjustable means for mounting electrical controls and more particularly to such means for positioning such controls upon the stack 5 of furnaces or upon the furnaces proper to control the operation of an electric motor for operating a fluid fuel burner or an electric fan or other electrically operated mechanism employed in producing or regulating 10 the heat within the furnace.

A type of commercial control for the above purpose includes an electric switch in the motor circuit, or control circuit for the motor, mounted within a casing having a tubular extension to enter within the furnace or stack of the furnace and support a thermal switch actuating member and operative connections therefrom to the switch, such as disclosed in this applicant's prior Patent No. 1,762,183 dated June 10, 1930. It is necessary to secure the tubular extension from the control casing to the wall or stack of the furnace so as to position the control mechanism in as nearly a horizontal position as possible. The walls 25 of hot air furnaces and the walls of the stacks from most furnaces at the points where it is preferable to apply the said control are usually at an angle to the vertical, especially in hot air furnaces, and it is an object of this invention to provide a means for readily mounting such controls at the point desired irrespective of the angle of the wall through which it enters.

With this and other objects in view reference is made to the accompanying sheet of drawing which illustrates a preferred embodiment of this invention with the understanding that minor detailed changes may be made without departing from the scope 40 thereof.

In the drawing—

Figure 1 is a view in side elevation illustrating an embodiment of this invention, showing the tubular control member engaged thereby and broken away;

Figure 2 is a view in front elevation of Figure 1, with parts broken away and partly in section;

Figure 3 is an enlarged detail view of the positioning member, with the tubular control

member indicated in dot and dash lines; and

Figure 4 is a view in perspective illustrating the application of this improved mounting to an inclined wall.

In the embodiment of this improved mounting only the tubular member 1 of the control mechanism which passes through the wall of the stack or furnace is shown. The mounting includes an attaching plate 2, preferably circular in form, having perforations 3 for the passage of rivets or bolts 4 for securing this plate to the exterior of the wall 5 of the stack or furnace. The attaching plate 2 is provided with a central rectangular opening 6 with a right angular extension 7 at one side thereof. A receiving member 8, preferably cylindrical in form, having trunnions 9 is mounted within the opening 6 with the trunnions in engagement with semicircular bearings 10 struck up from the back of the attaching plate. It is preferable to provide the trunnion adjacent the extension 7 with an enlarged shoulder 11 and to cut away that portion of the plate, as at 12, to receive the enlarged shoulder 11, as shown in Figure 1.

The cylindrical receiving member 8 is adapted for rotation within the rectangular opening 6 with its axis in the plane of the attaching plate 2. To hold the receiving member 8 in position and to secure it in desired relation to the attaching plate 2, the right angular extension 7 of the attaching plate 2 at one side of the rectangular opening 6 is provided with an arcuate slot 13 concentric with the trunnions 9. The cylindrical receiving member 8 is provided with a diametrical passage way 14 adapted to receive the tubular member 1 of the control, the circumference of which is intersected at right angles at one side by a positioning member 15, preferably cylindrical in form, with a contracted opening adjacent the extension 7 and with the center line of the passage way 15 arranged on a radius corresponding to the radius of the center of the arcuate slot 13. A shouldered positioning member 16 having a reduced screw threaded extension 17, and an arcuate undercut portion 18 upon the body is inserted through the passage way 15 with the screw threaded portion

100

17 extending through the arcuate slot 13. The radius of the arcuate undercut 18 is slightly greater than that of the tubular control member 1. A nut 19, and preferably a 5 washer 20, are mounted upon the screw threaded portion 17 of the positioning member to engage the exterior of the extension 7, whereby after the receiving member and parts have been assembled on the attaching plate, 10 the wall of the stack or furnace cut out to correspond to the plate opening 6 and the plate 2 secured to the wall, the tubular member 1 is inserted the desired distance through the passage way 14 and the receiving member 15 rotated until the tubular member 1 is substantially horizontal, the taking up of the nut 19 will hold the same in that position by the arcuate undercut 18 being drawn into contact with the tubular member and the engagement of the nut 19 with the exterior of the extension 7. To obtain the maximum amount of rotation possible of the tubular member the attaching plate 2 is provided with embossings 21, conforming in shape to the 20 tubular member, on opposite sides of the rectangular opening 6 and on reverse sides of the plate, as shown, to receive the tubular member when it has been rotated to the limit.

What I claim is:

1. An adjustable mounting for thermostatic controls upon furnaces, said control having a cylindrical member passing through the wall thereof, including an attaching plate, a cylindrical receiving member having a 35 diametrical passage way, adapted to receive the cylindrical member of the control, rotatably mounted upon said plate, and means in adjustable engagement with said plate and carried by the receiving member for 40 positioning the cylindrical member therein and securing the receiving member against rotation.

2. An adjustable mounting for thermostatic controls upon furnaces, said control 45 having a tubular member passing through the wall thereof, including an attaching plate, a cylindrical receiving member having a diametrical passage way, adapted to receive the tubular member of the control, trunnions upon each end of the receiving member, 50 said plate provided with an aperture and struck up portions on each side to provide bearings for said trunnions, and means holding the trunnions in engagement with the 55 plate, said means having adjustable engagement with the plate for positioning the tubular control member and locking the receiving member.

3. An adjustable mounting for thermostatic controls upon furnaces, said control 60 having a tubular member passing through the wall thereof, including an attaching plate, a cylindrical receiving member having a diametrical passage way, adapted to 65 receive the tubular member of the control,

trunnions upon each end of the receiving member, said plate provided with an aperture and struck up portions on each side to provide bearings for said trunnions, and means holding the trunnions in engagement with the plate, said means having adjustable engagement with the plate for positioning the tubular control member and locking the receiving member to a portion of the plate bent at right angles to the body at one side of the opening, and means having sliding engagement with said bent up portions of the plate for holding the trunnions against the bearings, and means upon said first means for engaging the tubular control member 80 and locking the receiving member.

4. A mounting for cylindrical members for both longitudinal and rotative adjustment including an attaching plate provided with a central aperture, a cylindrical receiving member mounted for rotation therein, and provided with a diametrical passage way for receiving the cylindrical member, a positioning member carried by said receiving member adapted to adjustably engage the cylindrical member and a portion of the attaching plate and means for locking the positioning member to hold the cylindrical member against longitudinal movement through the receiving member and at the same time hold the receiving member against rotation.

5. A mounting for tubular members for both longitudinal and rotative adjustment including an attaching plate provided with a central aperture, said plate having a right angular extension at one side thereof provided with an arcuate slot and struck up bearings on opposite sides of said aperture concentric with said arcuate slot, a cylindrical receiving member having trunnions adapted to be received in said bearings and having a diametrical passage way adapted to slidably receive the tubular member, a positioning member mounted for movement within the receiving member at right angles to said passage way and intersecting a portion thereof, said positioning member provided with an arcuate undercut portion permitting longitudinal movement of the tubular member and an extension at one end passing through the arcuate slot to hold the trunnions in the bearings, and means upon the exterior of the positioning member to engage the exterior of the slotted extension to cause the positioning member to engage the tubular member to prevent longitudinal movement thereof through said passage way and at the same time prevent rotation of the cylindrical receiving member.

IRA E. McCABE.
